SNOWPLOW

Louis Du Pras, Marquette, Mich.

Application July 23, 1945, Serial No. 606,546

10 Claims.

(Cl. 37—42)

1

This invention relates to apparatus for removing snow and other material from roadways, and more specifically relates to a motor propelled snowplow including a diagonally disposed moldboard for clearing roadways or for following other snowplows. It has heretofore been the practice, in clearing snow from highways, to merely push the snow to the sides of the road. Such road clearance causes the building up of snow banks on each side of the road. Furthermore, many places along the highways are subject to natural snow drifts alongside of the road. Whenever a snow bank is formed, either artificially or naturally, alongside of a road, snow is apt to drift adjacent the snow bank and cover the road. It is therefore important to remove these snow banks from the sides of the road, and the device of this invention is adapted for such removal by distributing snow over a wide roadside area by propelling the snow at great distance from the road.

In the past, it has generally been attempted to reduce the height of the roadside deposit by operating the snowplow at high speed to toss the snow over a wide area but this expedient is not successful where roadside obstructions are frequently encountered or where deep or wet snow is cleared, particularly on grades or curves.

In prior devices, various mechanical movement schemes involving feed screws, paddle wheels, moving blades and the like have been used to effect wider scattering of the snow. One disadvantage of such schemes is that the structures are often large and cumbersome and sometimes constitute obstructions preventing normal movement of snow across the moldboard. Also, it is generally difficult to transmit mechanical movements from a power source on the vehicle to a movable element in an adjustable moldboard.

It is then an object of this invention to provide novel apparatus for removing snow and other materials from roadways which is devoid of the above stated disadvantages of prior art devices.

A more specific object of this invention is to provide a novel moldboard structure particularly useful on snowplows for effectively removing snow from roadways by blowing or pneumatically blasting the scraped snow over wide areas of the roadside.

A more specific object of this invention is to provide a snowplow including a moldboard which involves a novel air pressure manifold structure which is effective to blow a controlled blast of air at a small angle to the face of the moldboard so as to move snow substantially along the face of the moldboard toward the trailing edge so as to blow the snow laterally of the vehicle and scatter it over a wide roadside area, thus eliminating the formations of high snow banks.

Other objects and advantages of this invention will become apparent to those skilled in the art

from the following detailed description of the annexed sheets of drawings which disclose a preferred embodiment of the invention.

On the drawings:

5 Figure 1 is a front elevational view of a snowplow embodying the novel features of this invention, illustrating the manner in which the moldboard of the snowplow is carried by a truck;

10 Figure 2 is a rear elevational view of the truck and moldboard shown in Figure 1;

Figure 3 is a cross-sectional view taken along line III—III of Figure 1;

15 Figure 4 is a longitudinal cross-sectional view taken through one of the three manifolds illustrated in Figures 1 and 2, and

15 Figure 5 is a cross-sectional view taken along line V—V of Figure 4.

Referring more particularly to Figures 1 and 2 of the drawings, numeral 10 denotes, generally, 20 a motor truck having a driver's cab 11 and a platform back 12. An auxiliary motor 13 and compressor 14 driven thereby are mounted on the platform back 12.

The main chassis of the motor truck 10 carries a superstructure extending upwardly in front of the cab 11 which carries a sheave (not shown) 25 for the purpose of pulling up the moldboard when desired as shown in detail in my Patent No. 2,115,790, filed May 19, 1937, entitled "Snowbank cutter" of which the present application is an improvement, which sheave, however, forms no part of the present invention.

As best shown in Figure 1, the main frame of the motor truck 10 carries near the front end 30 thereof a bracket 20 to which is swivelled a platform 21 extending over the front wheel of the truck. The platform 21 may have an opening in the central portion thereof for allowing the top of the wheel to extend above the platform.

40 The outer end of the platform 21 has two downwardly extending arms 23 having bosses 24 on the ends thereof. One or both arms 23 can be provided with a housing portion 25 extending downwardly therefrom below its boss 24 for receiving the shank 26 of a wheel mounting 27 carrying a supporting wheel 28.

The platform 21 can thus be held in any desired spaced relation from the ground by adjusting the position of the shank 26 in the housing 25. The wheel 28 will hold the outer end of the platform 21 in the desired horizontal position.

50 A moldboard or cutter 30 is formed of comparatively light weight sheet metal and has a front face adapted to scoop up or sweep snow. The moldboard is preferably arcuate in shape and flared outwardly as illustrated although it may be flat or curved or of other shapes as desired.

60 A plurality of manifolds, for example, three of them designated by numerals 31, 32 and 33, are

rigidly mounted on the rear face of the moldboard. Air under pressure is fed to these manifolds by means of the motor driven compressor 14 which feeds air under pressure to manifold 15, thence through conduits 36, 37 and 38 to manifolds 31, 32 and 33 respectively. Suitable supporting rods 35 and 39 are provided for manifolds 31 and 32, respectively.

As shown in Figure 1, wherein manifold 32 is shown in dotted lines since it is mounted on the rear of the moldboard, a plurality of openings, such as 40 to 43 inclusive, are provided on the moldboard for allowing communication between the manifold and front surface or face of the moldboard and through which air under pressure is blown for expelling snow or other material from such face.

As best shown in Figure 3 the construction of the three manifolds, 31, 32 and 33 may be identical. Furthermore the elongated manifolds are disposed in spaced relationship substantially parallel to each other and to the roadway surface. It will be understood, of course, that any other number of manifolds may be provided and may be spaced differently if so desired, or perhaps only one large manifold may be used. However by properly positioning a plurality of manifolds more effective removal of snow from the face of the moldboard is obtained.

The novel internal construction of each of the manifolds is best illustrated in Figures 4 and 5 showing, for example, manifold 32. A plurality of baffle plates, such as 45 and 46 are provided, one for each opening, and are rigidly secured to the rear surface of moldboard 30, being disposed at a small angle relative to said surface so as to direct air under pressure at a small angle to the front surface of the moldboard in a direction towards the trailing edge thereof so as to eject or blow snow substantially parallel to the face of the moldboard laterally of the direction of movement of the truck.

Dampers, such as 50 and 51, are provided adjacent each of the baffles and have swingable arcuate edges having shapes corresponding with the shape of the rear surface of the moldboard thereby being adapted to prevent the flow of compressed air through the openings when the dampers are in the closed position. The other ends of the dampers are integrally secured to sleeves 65 and 66 which are journaled about rods such as 47 and 48 secured to the manifold wall adjacent the inwardly projecting ends of the baffle plates. Crank arms, such as 59 and 60, are also rigidly secured to sleeves 65 and 66 and fixed with respect to dampers 50 and 51, respectively, the other ends of which arms are pivotally secured to sleeves 61 and 62. The pivotal connections between crank arms 59 and 60 and sleeves 61 and 62 are made sufficiently loose in the vertical direction of Figure 4 to permit movement of rod 53 without tending to deform baffles 45 and 46. These sleeves are rigidly secured in spaced relationship to rod 53 by screws 63 and 64, respectively. Rod 53 is slidably mounted on brackets such as 54 and 55 rigidly fixed to the wall of the manifold. Spring 56 having one end abutting against bracket 54 and the other end confined by a nut 57 screw threaded on rod 53 biases the rod 53 to the left, as illustrated, that is, to the closed position of the dampers.

In operation, when a predetermined amount of air pressure is built up in the manifold, perhaps of the order of 50 to 75 pounds per square inch, that is, sufficient to overcome the tension

of spring 56 the dampers are opened to a degree which is proportional to the pressure, therefore allowing a blast of air under pressure to go through the openings 40 to 43 inclusive at an angle determined by the slope of the baffle plates to blow snow away from the front surface of the moldboard.

By unscrewing a threaded cap 58 so as to gain access to nut 57 such nut may be screwed so as to place any desired tension on spring 56 so as to adjust the value of air pressure necessary for opening the dampers. Thus the air blast may be effectively and simply controlled so as to meet various conditions encountered, such as different wetness of snow, different heights of snow etc.

While the moldboard has been illustrated as being disposed diagonally on the side of the truck it should be understood that it may be disposed in front of the truck as well. Also, the moldboard instead of being arcuate-shaped may be flat or may be V-shaped or any other shape desired.

Thus it will be seen that I have provided an efficient and easily controlled pneumatically operated snowplow for effecting blowing of snow over a wide side area of the roadway thereby preventing the building up of snow banks.

I am aware that many changes may be made and numerous details of construction may be varied through a wide range without departing from the principles of this invention, and I, therefore, do not propose limiting the patent granted hereon otherwise than necessitated by the prior art.

I claim as my invention:

1. In combination, a snowplow moldboard having a plurality of manifolds mounted in spaced relationship on the rear surface thereof, the face of said moldboard being apertured at places corresponding with the positions of said manifolds to communicate therewith, angularly disposed baffle plate means in said manifolds adjacent said apertures for directing compressed air developed in said manifolds substantially along the faces of said manifolds, and damper means disposed in the path of air flow from said manifolds to said apertures to control the passage of air therethrough.

2. In combination, a snowplow moldboard having a plurality of longitudinally-extending manifolds mounted on the rear surface thereof, a plurality of apertures being formed on said moldboard to correspond to the position of each of said manifolds and communicating therewith, each of said manifolds containing an angularly disposed baffle plate adjacent each aperture and a damper rotatably mounted in each path of air flow from said manifold to each of said apertures to adjust the flow of air through said apertures to direct a controlled blast of air at a small angle with the face of said moldboard.

3. A moldboard having mounted on the rear surface thereof a plurality of longitudinally-extending manifolds in spaced-parallel relationship, a plurality of apertures in said moldboard communicating with each of said manifolds, an angularly extending baffle plate in said manifold adjacent each aperture, a plurality of dampers in said manifold, one for each aperture to control the blast of air ensuing from the manifold, and spring biased means tending to move all of said dampers to the closed position, said dampers being openable upon attainment of a predetermined

air pressure in said manifold that overcomes the action of said spring biased means.

4. A snowplow moldboard having mounted cross-wise on the rear surface thereof a plurality of elongated manifolds arranged in spaced parallel relationship, a plurality of holes extending through said moldboard communicating with each of said manifolds, a plurality of angularly disposed baffle plates in said manifold, each disposed adjacent the periphery of one of said holes, a damper pivotally mounted adjacent the inwardly projecting end portion of each of said baffle plates, a longitudinally extending rod in each manifold operatively fastened to all of the dampers, and adjustable spring means tending to move said rod to maintain said dampers in the closed position, said dampers being openable upon the attainment of a predetermined air pressure depending upon the adjustment of said spring means.

5. In combination with a traction vehicle, a moldboard mounted diagonally of said vehicle in position for scraping the surface over which said vehicle travels, manifold means mounted on the rear surface of said moldboard, apertures in said moldboard communicating with said manifold means, and spring biased damper means contained within said manifold means to normally block communication through said apertures to the front surface of said moldboard and to allow free communication therethrough only upon attainment of a predetermined air pressure in said manifold means to direct a fluid blast along the surface of the moldboard in the direction normally travelled by material being scraped thereby.

6. In combination with a traction vehicle, a moldboard mounted diagonally of said vehicle in a position for scraping the surface over which said vehicle travels, a plurality of manifolds mounted on the rear of said moldboard, arranged in substantially parallel, spaced relationship with each other and with the surface of the roadway, a plurality of apertures extending through said moldboard in communication with each of said manifolds, spring-biased damper means disposed in each manifold and tending to close communication with the front surface of said moldboard through said apertures, and baffles mounted in said manifold to direct a blast of air substantially along the front surface of the moldboard in the direction of travel of material scraped off thereby, said damper means being openable only upon attainment of a predetermined air pressure sufficient to overcome the bias of said spring biased damper means.

7. In combination with a traction vehicle, a moldboard mounted diagonally of said vehicle in position for scraping the surface over which said vehicle travels, a plurality of manifolds mounted on the rear of said moldboard, arranged in substantially parallel, spaced relationship with each other and with the surface of the roadway, a plurality of apertures extending through said moldboard in communication with each of said manifolds, a plurality of baffle plates in each of said manifolds, each baffle plate being disposed so as to direct a blast of air from said manifold angularly through the corresponding aperture, a damper pivotally mounted adjacent each baffle plate, and spring operated means for normally moving said dampers to close communication through said apertures, the bias of said spring operated means being overcome to open the dampers by attainment of a predetermined air pressure in the manifold so as to direct a blast of

air along the front surface of said moldboard in substantially the direction of travel of material normally scraped thereby.

8. A snowplow comprising a traction vehicle, a snowplow moldboard mounted diagonally of the vehicle, said moldboard having mounted on the rear thereof a plurality of elongated manifolds spaced in substantially parallel relationship with each other and with the surface of the roadway which said moldboard is to scrape, a plurality of holes extending through said moldboard and communicating with each of said manifolds, means including damper means inside each of said manifolds for directing a blast of air along the snow engaging surface of said moldboard upon the attainment of a predetermined air pressure in the manifold, and air compressor and delivery means on said vehicle for supplying air under pressure to said manifolds.

20 9. A snowplow comprising a traction vehicle, a snowplow moldboard mounted diagonally of the vehicle, said moldboard having mounted on the rear thereof a plurality of elongated manifolds spaced in substantially parallel relationship with each other and with the surface of the roadway which said moldboard is to scrape, a plurality of holes extending through said moldboard and communicating with each of said manifolds, baffle plates in each of said manifolds disposed angularly adjacent the periphery of said holes for directing a blast of air substantially along the snow engaging surface thereof toward the trailing edge of said moldboard, a damper for each of said holes and being contained within the manifold, and spring biased operating means for normally closing all of said dampers simultaneously to close communication through said holes, the bias of said spring biased operating means being overcome by attainment of a predetermined air pressure in said manifolds.

10 10. A snowplow comprising a traction vehicle, a snowplow moldboard mounted diagonally of the vehicle, said moldboard having mounted on the rear thereof a plurality of elongated manifolds, spaced in substantially parallel relationship with each other and with the surface of the roadway which said moldboard is to scrape, a plurality of holes extending through said moldboard and communicating with each of said manifolds, baffle plates in each of said manifolds, disposed angularly adjacent the periphery of said holes for directing a blast of air along the snow engaging surface thereof towards the trailing edge of said moldboard, a damper pivotally mounted adjacent each of said baffle plates to control the passage of air through said holes, spring operated means for simultaneously moving all of said baffle plates to a position to block passage of air through said holes, the bias of said spring operated means being overcome in proportion to the air pressure developed in the manifold to proportionally open the dampers to allow a blast of air to be blown against the snow engaging surface of the moldboard.
